U.S. Non-Final Office Action dated Aug. 28, 2018 received in U.S. Appl. No. 29/571,996.

Primary Examiner — W. A. Teddy Falloway

(74) Attorney, Agent, or Firm — Scully, Scott, Murphy & Presser, P.C.

(57) CLAIM

The ornamental design for a carrier, as shown and described.

DESCRIPTION

The patent file contains at least one drawing executed in color. Copies of this patent with color drawings will be provided by the Office upon request and payment of the necessary fee.

FIG. 1 is a perspective view of a carrier showing our new and ornamental design;

FIG. 2 is a top view thereof;

FIG. 3 is a side view thereof; and,

FIG. 4 is a front view thereof.

The side view depicted in FIG. 3 is a mirror image of the opposite side view, which is not depicted herein. The front view depicted in FIG. 4 is a mirror image of the back view, which is not depicted herein.
